(57) **CLAIM**

The ornamental design for a pressure washer, therefor as shown and described.

DESCRIPTION

FIG. 1 is a front right perspective view of the pressure washer according to the invention.

FIG. 2 is a front left perspective view of the pressure washer according to the invention.

FIG. 3 is a rear left perspective view of the pressure washer according to the invention.

FIG. 4 is a rear right perspective view of the pressure washer according to the invention.

FIG. 5 is a front view of the pressure washer according to the invention.

FIG. 6 is a rear view of the pressure washer according to the invention.

FIG. 7 is a left side view of the pressure washer according to the invention.

FIG. 8 is a right side view of the pressure washer according to the invention.

FIG. 9 is an enlarged top view of the pressure washer according to the invention; and,

FIG. 10 is an enlarged bottom view of the pressure washer according to the invention.

The broken lines in the figures illustrate portions of the pressure washer which form no part of the claimed design.

1 Claim, 10 Drawing Sheets
